VENDING MACHINE FOR DISPENSING CIGARETTES, CANDY OR THE LIKE

William W. Carter and Charlie F. Carter, both of Rte. 1, Brundidge, Ala.

Filed Sept. 12, 1960, Ser. No. 62,121

Term of patent 14 years

(Cl. D52—3)

The figure is a front perspective view of a vending machine for dispensing cigarettes, candy or the like, showing our new design. The undisclosed side of the vending machine is substantially the same in appearance as the side shown, and the rear is substantially plain.

We claim:

The ornamental design for a vending machine for dispensing cigarettes, candy or the like, as shown and described.
